UNITED STATES PATENT OFFICE.

ALBERT BOCK, OF BRUNSWICK, GERMANY, AND WALTER A. KRAMER, OF CHAMBERSBURG, PENNSYLVANIA.

GRINDING-MILL.

No. 925,987.

Specification of Letters Patent. Patented June 22, 1909.

Application filed January 30, 1907. Serial No. 354,926.

To all whom it may concern:

Be it known that we, ALBERT BOCK, a subject of Germany, residing at Brunswick, Germany, and WALTER A. KRAMER, a citizen of the United States, residing at Chambersburg, in the county of Franklin and State of Pennsylvania, have invented certain new and useful Improvements in Grinding-Mills; and we do hereby declare the following to be a full, clear, and exact description of the invention, such as will enable others skilled in the art to which it appertains to make and use same, reference being had to the accompanying drawings, and to the characters of reference marked therein, which form a part of this specification.

This invention relates to new and useful improvements in grinding mills for grain, etc., and relates particularly to the provision of adjusting mechanism whereby the fracture to the runner heads may be prevented, in the event of any foreign substances entering the mill.

The invention consists further in various other details of construction and combinations and arrangements of parts which will be hereinafter fully described and then specifically defined in the appended claims.

Our invention is illustrated in the accompanying drawings, in which:—

Figure 1 is a side elevation of our improved grinding mill apparatus. Fig. 2 is a vertical sectional view through the machine. Fig. 3 is a sectional view vertically through a hopper and feeding shoe. Fig. 4 is a similar view showing the modified form of the hopper, and Fig. 5 is a sectional view showing the feeding mechanism adapted principally for feeding alfalfa or other material of a similar nature which would not under ordinary circumstances feed readily without the screw conveyor, and Fig. 6 is an enlarged detail in side elevation of the hopper. Fig. 7 is an enlarged detail view showing the means for adjusting the sectional shaft and the right and left threaded lever for moving the sections of the shaft longitudinally in opposite directions.

Reference now being had to the details of the drawings by characters, A and A' designate two shafts mounted in suitable bearings B upon the pedestals B'. A vertically disposed grinding head C having a hub portion C' is fixed to the shaft A and rotates within a casing E. C² designates a second grinding

head which is fixed to and rotates with the shaft A', said grinding head C² having a hub C' fixed to the shaft A', said shaft A' being adapted to have a slight longitudinal movement, whereby adjustments can be made but is fixed rigid, longitudinally, when the mill is fixed for grinding.

At one end of the shaft A is a bearing disk E fixed thereto and the outer face of said disk is provided with an annular groove to receive the ball bearings E², which bearings also engage a groove formed in the bottom of the cup E³. E' is an apertured disk in which said shaft A has a loose bearing and the circumference of the disk E' engages threads formed in the inner surface of said cup. By this construction, it will be noted that a swivel connection is provided between the cup and the disk E upon the shaft A. F is a casing or shell in which said cup has a longitudinal play, and is provided with an opening F' through which access may be had to the interior thereof. A stem F² projects from said cup and may be closely fitted to or have a play through an opening in the end of the shell or casing F. G designates a link which is pivoted at G' to a bracket arm G² of the shell or casing F, and H is a lever pivotally connected upon a pin H' carried by said stem F² and carries a pivot pin H² which is pivotally connected to the link G. Said shell or casing is provided with a suitably braced flange F³ which is bolted or otherwise secured to the flange I integral with the casing containing the bearing B.

J designates a shaft which is mounted to have a longitudinal movement in a sleeve K carried by the lever H, said shaft J being splined within the sleeve and has an adjusting wheel Q fitted upon its outer threaded end, thus affording means whereby the lever H may be adjusted, which adjustment will act upon the stem F² and thus enable the heads to be adjusted for grinding any degree of fineness. The inner end of the shaft J has a coarse thread P which engages threads formed in the wall of an opening in the double-threaded handle releasing notch R. J' designates a second shaft which is mounted to have a longitudinal play in registering apertures in the flanges F³ and I, and is splined to said flanges. Said shaft J' has left threads at its inner end adapted to engage corresponding threads formed in the opening in said releasing double-

threaded nut R, and J² is a collar which is keyed to the shaft J' and serves to prevent a movement in one direction beyond a certain limit.

5 N designates a casing which is open at one end and contains a coiled spring O which bears between the transverse partition O' within said casing and a plunger N' which is mounted upon the outer threaded 10 end of the shaft J', being held in place by means of the nut O². Said plunger is of such a diameter as to move within the casing N as the shaft J' is moved longitudinally toward the releasing lever, in which 15 movement said spring is put under tension.

C⁵ is a hopper which has a passageway leading to the space intermediate the grinding disks, and mounted within said hopper is a shoe T pivoted upon a pin T', which latter is mounted in an eye in a pin T^x which is vertically swiveled, thereby allowing the shoe to have both a lateral and a vertical vibratory movement.

T² designates a hand wheel mounted upon 25 a screw T³ which is threaded to receive said wheel, and the lower end of said screw is connected to a rod T⁴ fastened to the shoe, whereby the shoe may have vertical adjustment.

30 T⁵ designates a shaft upon which the pulley T⁶ is mounted, and an eccentric T⁷ rotates with the shaft T⁵ and is designed to give the shoe a lateral movement as the pulley T⁶ is rotated.

35 In order to provide extra precautionary means to hold the grinding disks separate, in the event of any foreign substance getting between the same, we make the pin H', which pivotally connects the lever H 40 with the stem F², of a breakable material. An eye h' is fastened to the end of the stem F², and h² is a wire connected to said eye and passes over suitable pulleys h³ and is connected to an angle lever t, one end of 45 which bears against the under side of the hand wheel T², whereby in the event of the pin H' breaking, by reason of extra pressure coming upon the same by the separation of the grinding heads, the feeding to 50 the machine may be stopped by the wire raising the shoe.

Referring to Fig. 5 of the drawings, will be seen a slight modification of the construction of the apparatus, whereby the 55 same is adapted for use in feeding alfalfa or other material of a like nature, to the grinding heads. In said figure is shown a shaft W mounted beneath the hopper, and projecting from said shaft are the feeding 60 fingers W', whereby alfalfa or other material of a like nature may be conveniently fed to the grinding heads. L designates a conveyer worm which is loosely mounted upon the shaft A' and has a chambered por-

tion which is adapted to telescope over the 65 hub E², and the portion of said conveyer which projects outside the casing of the hopper in which it has a bearing, forms a pulley A⁴ about which a belt A⁵ passes, which belt also passes about a pulley A⁶ 70 fixed to the shaft W, and W² designates a second pulley which is fixed to the shaft W and has connection, through the medium of the belt W⁴, with a pulley W⁶ which is fixed to the shaft A', thereby affording means 75 whereby power may be imparted to the shaft W and also to the conveyer. While we have shown the conveyer as chambered and adapted to receive the hub of the grinding head C², if preferred, said conveyer may 80 be made to contact with the outer end of the hub.

It will be noted upon reference to Fig. 5 of the drawings that the end of the shaft A' is mounted in a shell A⁷ which is mounted within the hollow shell A⁸ which is fixed to the shaft A, and affords means whereby the two grinding heads may be centered and kept in proper relation to each other, even though the grinding head C has a movement 90 away from or toward the grinding head C².

In operation, in the event of any foreign substance such as a piece of metal or other hard material getting into the mill and between the grinding disks and the same is detected, the quick manipulation of the releasing lever R will cause a longitudinal movement to be imparted to the shaft J, which, through its connections with the cup E², will cause a longitudinal movement to be imparted to the shaft A, which will cause the grinding heads to separate without interfering with the adjustment of the mill. It will be understood that, when the right and left threaded nut R is moved in one direction, the 100 collar J² will come in contact with the standard I and prevent the longitudinal movement of the shaft J' in one direction while the shaft J is quickly moved to the left. The 105 grinding heads may also be automatically withdrawn from each other by the shaft A bearing against the cup and through the connections of the latter with the shafts J and J', will cause the latter to move under the 110 tension of the spring O, and after the foreign substance is free from the grinding heads, the spring about the shaft J' will cause the heads to assume their normal positions.

By the provision of the mechanism connected with the shoe, the latter may be adjusted when in motion or stationary, thereby regulating the feed and enabling the shoe to be wide open if desired.

What we claim is:—

1. A grinding mill comprising two rotatable shafts, one of which is adapted to have a longitudinal movement, a grinding head secured to each shaft, a spring-actuated

threaded shaft, a stem having swivel connection with said longitudinally movable shaft, a lever having pivotal connections with said stem, a link pivoted to the frame of the apparatus at one end and its other end to said lever, a threaded shaft supported in a suitable bearing on said lever, a wheel upon the outer threaded end of said shaft carried by the lever, a double-threaded handled releasing nut engaging the adjacent threaded ends of the spring-actuated and lever supporting shafts, as set forth.

2. A grinding mill comprising two rotatable shafts, one of which is adapted to have a longitudinal movement, a grinding head secured to each shaft, a stem swiveled to the longitudinally movable shaft, a pivotal lever connected to said stem, a threaded shaft supported by said lever, a spring actuated threaded shaft, a double-threaded handled nut engaging the adjacent threaded ends of said spring-actuated and lever supporting shafts, a feeding hopper, a vibrating shoe in said hopper, a rotatable cam for vibrating said shoe, a shaft upon which the cam is mounted, connections between said stem and shoe and adapted for raising the latter in the event of foreign matter entering between the grinding heads and imparting a longitudinal movement to said stem, as set forth.

3. A grinding mill comprising two rotatable shafts, one of which is adapted to have a longitudinal movement, a grinding head secured to each shaft, a stem swiveled to the longitudinally movable shaft, a pivotal lever connected to said stem, a threaded shaft supported by said lever, a spring actuated threaded shaft, a double-threaded handled nut engaging the adjacent threaded ends of said spring-actuated and lever supporting shafts, a feeding hopper, a vertically pivoted pin within said hopper, a vibrating shoe mounted in an eye in said pin, a rod pivotally connected to the free swinging end of the shoe, a button fixed to said rod, a bell crank lever engaging said button, and connections between said angled lever and said stem and so arranged that, as the stem is

moved in one direction, the shoe may be 50 raised, as set forth.

4. A grinding mill comprising two rotatable shafts, one of which is adapted to have a longitudinal movement, a grinding head secured to each shaft, a spring-actuated 55 threaded shaft, a stem having swiveled connection with said longitudinally movable shaft, a lever having pivotal connections with said stem, a link pivoted to the frame of the apparatus at one end and its other 60 end to said lever, a threaded shaft mounted in suitable bearings upon said lever, a wheel upon the outer threaded end of said shaft carried by said lever, a double threaded handled releasing nut engaging the adjacent 65 threaded ends of the spring-actuated and lever supporting shafts, a plunger fixed to said spring-actuated shaft, a casing in which the plunger is mounted, a collar fixed to the spring-actuated shaft, and a standard 70 adapted to limit the movement of the collar in one direction, as set forth.

5. A grinding mill comprising two rotatable shafts, each of which is adapted to have a longitudinal movement, a grinding 75 head secured to each shaft, one of said shafts having a disk, a cup shaped member, a shell in which the latter is mounted, ball bearings intermediate the bottom of the cup and the disk, means for holding the latter within 80 the cup, a stem integral with said cup and extending through an aperture in said shell, a lever pivoted to said stem, link connections between said lever and shell, a threaded shaft carried by said lever, adjusting wheel 85 upon said threaded shaft, a spring-actuated shaft having a threaded end, a double threaded handled nut engaging the adjacent ends of said spring-actuated and lever supporting 90 shafts, as set forth.

In testimony whereof we hereunto affix our signatures in the presence of two witnesses.
